UNITED STATES PATENT OFFICE.

JONATHAN L. KNIGHT AND HENRY W. ROBY, OF TOPEKA, KANSAS; SAID KNIGHT ASSIGNOR TO SAID ROBY.

CLOTHES-LINE APPARATUS.

SPECIFICATION forming part of Letters Patent No. 743,001, dated November 3, 1903.

Application filed July 25, 1902. Serial No. 116,983. (No model.)

To all whom it may concern:

Be it known that we, JONATHAN L. KNIGHT and HENRY W. ROBY, citizens of the United States, residing at Topeka, in the county of 5 Shawnee and State of Kansas, have invented new and useful Improvements in Clothes-Line Apparatus, of which the following is a specification.

Our invention relates to improvements in 10 clothes-line apparatus, and has for its general object to provide an apparatus which while simple, inexpensive, and light in construction is calculated to materially facilitate the putting up, stretching, and fastening of 15 a clothes-line, as well as the taking down and removal of the line indoors or out of the weather, and is also well adapted to withstand the usage to which such devices are ordinarily subjected.

With the foregoing in mind the invention 20 will be fully understood from the following description and claims when taken in conjunction with the accompanying drawings, in which—

Figure 1 is a side elevation of our improved apparatus with all of the parts in their proper operative positions and the reel-frame partly in section; Fig. 2, a front elevation of the same; Fig. 3, an enlarged detail section taken 25 through the reel and reel-frame of the apparatus in the plane indicated by the broken line 3 3 of Fig. 1; Fig. 4, an enlarged detail section taken in the plane of the broken line 4 4 of Fig. 1 and illustrating the manner in 30 which the latch on a support engages the reel-frame to secure the latter in its operative position, and Fig. 5 an enlarged detail section taken in the plane indicated by the broken line 5 5 of Fig. 1 and illustrating the 35 bar for locking the reel to the reel-frame and the slide controlling said bar.

Similar letters of reference designate corresponding parts in all of the views of the drawings, referring to which—

A is a support, which may be either a post or the side of a building; B, a hook secured to said support; C, a shelf, preferably of sheet metal, also secured to the support, but in a plane below the hook and having an upwardly and inwardly inclined flange a at its outer edge; D, a vertically-slidable latch se-

cured to the support at a point above the shelf C and having a finger-piece a'; E, a block provided with a pulley b and an eye c, the latter to receive the hook B, on which the 55 block is removably hung; F, a reel, upon which a clothes-line G is designed to be wound; H, a reel-frame, and I a shaft, through the medium of which the reel is supported and turned in the frame. 60

The reel-frame H in the present and preferred embodiment of our invention is formed of metallic, preferably steel, straps, and comprises an oblique rectangular section d, an oblique bail-shaped section e, fixedly connected 65 at its ends to the side bars of the rectangular section and disposed at right angles thereto, and a central vertical section or bar f, interposed between and fixedly connected to the lower and rear cross-bar of the section d and 70 the cross-bar of the section e and provided above the latter with a horizontal portion g, having an aperture h to receive the latch D, Figs. 1 and 4. In the lapped portions of the sections d e are formed coincident apertures 75 i, designed to receive the shaft I, while in one arm of the section e is an aperture j, Figs. 1 and 3. This latter aperture is arranged in alinement with an aperture j' in a bracket k, fixed to the arm of the section e, and is designed for a purpose presently pointed out. 80

The reel F is preferably made up of circular sheet-metal disks l l' and a central tubular connection m interposed between the same, which tubular connection may be of 85 the construction shown in Fig. 3 or any other suitable construction without departing from the scope of our invention. As shown in Fig. 3, the tubular connection m comprises an outer tubular section having arms m' at one end connected to the disk l and an inner tubular section connected to the disk l' and arranged in the outer section. Said reel is arranged on the shaft I and in the frame H with its disk l, which has apertures n at intervals between 90 the bracket k and the apertured arm of the frame-section e, and it is detachably fixed to the shaft through the medium of a bolt J, which extends through coincident apertures in its tubular portion and the shaft, Fig. 3, 95 and has an eye p for the connection of the clothes-line, as shown.

K is a spring-bar for locking the reel F to the frame H. This bar has an annular arm q at one end connected to that arm of the frame - section in which the aperture j is formed, and it also has an angular branch r at its opposite end designed to pass through the coincident apertures j, j' and n of the frame and reel-disk l, respectively, and an inclined or cam portion s at an intermediate point of its length. Said bar K extends through an aperture t in a lateral arm u, carried by a slide M, which slide is secured on the apertured arm of the frame - section e. Consequently it will be seen that when the slide is moved in the direction indicated by arrow from the position shown in Fig. 3 the branch r of the locking-bar will be drawn out of engagement with the aperture j' in bracket k and the aperture n in reel-disk l, while when the slide is returned to the position shown in Fig. 3 the locking-bar will of itself return to the position shown, or, if no one of the apertures n in the reel-disk is coincident with the apertures j, j', to such position that its branch r bears against the disk l ready to spring into one of the apertures n thereof when the same becomes coincident with the apertures j, j'.

In practice the user of our improved apparatus first passes the clothes-line through the block E and then fastens one end of the line to the bolt J. She then turns the reel through the medium of the crank w on shaft I, and thereby winds the line in such manner that the block E is covered by the line as the winding progresses. When the winding of the line on the reel is completed, the user fastens one end of the line to a hook on a fence or other support in a yard or like place and then walks with the reel and reel-frame in hand and places the line successively in engagement with hooks located at points intermediate of the first-mentioned hook and the place where the shelf C and latch D are located. The block E, having been uncovered by the paying out or unwinding of the line, is now placed on the hook B, as shown in Figs. 1 and 2, after which the frame H is interposed and securely fastened between the shelf C and the latch D. With this done the reel is turned to stretch the line, and when the line is sufficiently taut the slide M is moved in a direction opposite to that indicated by arrow in Fig. 3, so as to enable the bar K to lock the reel to the frame after the manner before described, and thereby hold the line under tension.

We prefer to place the line and reel in the manner described above; but, if desired, the frame H may first be fixed on the support A and the line drawn off the reel and passed around the hooks on the support and then fastened at its outer end.

When it is desired to take in the line and remove it indoors or out of the weather, the latch D is raised and the frame H, reel F, and block E removed from the support A, after which the operator walks with the ap-

paratus and winds the line on the reel until the outer fastened end of the line is reached. Such end is then unfastened and the line is carried, with the reel and reel-frame, into the house.

If desired, the line may when in position be slackened in order to facilitate hanging of clothes thereon, and the slack may then be taken up and the line rendered taut through the medium of the reel.

By virtue of the line-guide, which is preferably in the form of a block containing a pulley or sheave, being arranged above the reel it fixes the height of the line independent of the height of the reel, and hence permits of the reel being placed at such a height above the ground that said reel may be conveniently operated by a person standing on the ground.

We have entered into a specific description of the construction and relative arrangement of the several parts embraced in the present and preferred embodiment of our invention in order to impart a full, clear, and exact understanding of the same. We do not desire, however, to be understood as confining ourselves to such specific construction and arrangement of parts, as such changes or modifications may be made in practice as fairly fall within the scope of our claims.

Having described our invention, what we claim, and desire to secure by Letters Patent, is—

1. In a clothes-line apparatus, the combination of a support, the shelf arranged thereon, and having the upwardly and inwardly inclined flange, a latch mounted on the support above the shelf, a reel-frame having an oblique section provided with a lower bar removably arranged on the shelf within the flange thereof, an oblique section extending upwardly and inwardly from the first-mentioned section, and an upright section connecting the cross-bars of the oblique sections and provided with a keeper adapted for the engagement of the latch, and a reel carried in the said frame.

2. In a clothes-line apparatus, the combination of a support, a shelf arranged thereon and having an upwardly and inwardly extending flange, a vertically-sliding latch secured on the support above the shelf, the reel-frame comprising the oblique, rectangular section the lower bar of which is removably arranged on the shelf within the flange thereof, the bail-shaped section disposed at an angle to and extending inwardly and upwardly from the side bars of the rectangular section, and the upright section connecting the lower cross-bar of the rectangular section and the cross-bar of the bail-shaped section, and having an upper horizontal portion provided with an aperture adapted to receive the latch, and a reel carried in the said frame.

3. In a clothes-line apparatus, the combination of a frame having sides one of which is provided with a transverse aperture, a reel

mounted in the frame and having a handle, and also having one or more transverse apertures adapted to coincide with that of the frame side, a spring locking-bar having an angular arm at one end connected to said side of the frame, and an angular branch at its opposite end adapted to enter the apertures in the frame side and reel-disk, and also having an intermediate inclined or cam portion, and a slide movable on the said apertured side of the frame and having an angular arm

provided with an aperture receiving the locking-bar.

In testimony whereof we have hereunto set our hands in presence of two subscribing witnesses.
